US00D944573S

(12) United States Design Patent (10) Patent No.: US D944,573 S
Gady et al. (45) Date of Patent: * Mar. 1, 2022

(54) RETAIL FIXTURE

- (71) Applicant: Apple Inc., Cupertino, CA (US)
- (72) Inventors: Jean-Marc Gady, Los Altos, CA (US); Gabriel J. Lamb, Burlingame, CA (US); Adrian E. Magrina, San Francisco, CA (US); Simona M. Szabados, San Francisco, CA (US); Moritz Wilsberg, Rheinbreitbach (DE)
- (73) Assignee: Apple Inc., Cupertino, CA (US)
- () Term: 15 Years
- (21) Appl. No.: 29/807,982
- (22) Filed: Sep. 16, 2021

Related U.S. Application Data

- (63) Continuation of application No. 29/706,332, filed on Sep. 19, 2019, now Pat. No. Des. 931,019.

Primary Examiner — Mary Ann Calabrese*Assistant Examiner* — Katelin G Kloberg*(74) Attorney, Agent, or Firm* — Sterne, Kessler, Goldstein & Fox P.L.L.C.CLAIM

The ornamental design for a retail fixture, as shown and described.

DESCRIPTION

FIG. 1 is a top front perspective view of a retail fixture showing the claimed design;

FIG. 2 is a bottom front perspective view thereof; and,

FIG. 3 is a front view thereof.

The dashed broken lines in the figures show portions of the retail fixture that form no part of the claimed design.

The dot-dash broken lines in the figures show boundaries that form no part of the claimed design.
